ABSTRACT OF THE DISCLOSURE

A deflasher which includes a tumbler for simultaneously supporting and turning workpieces in a dehumidifying housing wherein a freezing medium is applied to the workpieces so that excess material may be removed by abrasive blasting is characterized by applying the freezing medium, which is liquid nitrogen, at a rate of flow substantially independently of the storage pressure of the liquid nitrogen.

This invention relates to an apparatus for removing trimmings, flashings, fins, etc., from molded resilient pieces, and particularly to such an apparatus which applies liquid nitrogen to the pieces for freezing the excess material so that the pieces can be readily deflashed.

Apparatus for removing excess material from molded pieces by supporting and turning the pieces while they are subjected to the application of a freezing medium, have been devised heretofor. In these, the excess material is frozen and is easily removed by an abrasive blasting treatment. Some examples are described in U.S. Patent Nos. 3,110,983 and 2,996,846. Carbon dioxide or liquid nitrogen is used as the freezing medium.

The use of liquid nitrogen as the freezing medium has a number of distinct advantages over carbon dioxide. For example, a liquid nitrogen system is more economical when production volume is high enough to justify full time use of the system. Since liquid nitrogen boils off at the rate of 1 percent per day, intermittent use is not recommended. However, despite this boil-off, liquid nitrogen is still more economical.

Liquid nitrogen has a higher heat transfer coefficient than carbon dioxide with reference to the same part. This same relationship is true for example, when comparing nitrogen gas with carbon dioxide gas. Additionally, a larger percentage of the liquid nitrogen provides effective cooling than with carbon dioxide. The liquid nitrogen adheres to the workpieces and internal parts of the blast compartment as it boils off causing the refrigerant action; the carbon dioxide converts into 54 percent gas and 46 percent solid particles and it is the solid particles only that provide effective cooling. Since the dispersion of the solid particles of the carbon dioxide is a questionable point and since it is a known fact that some of these particles drop out of the blast compartment and never provide refrigerant action to the workpieces, equal weight of liquid nitrogen and carbon dioxide provide different cooling effects. Liquid nitrogen provides considerably greater temperature reduction. Moreover, lower temperatures are available from liquid nitrogen and therefore a wider selection of work can be deflashed; including silicone rubber compounds.

The net result of the above features is that less liquid nitrogen is required per batch and usually the batch cycle times are shorter. It is unrealistic to assign finite values to the generally expected savings of a liquid nitrogen system over a carbon dioxide system. The user, his operators, and the user's plant environment, not to mention the configuration of the various parts to be deflashed, put enough variables into the question to make a clear-cut answer im-

2

possible. However, a reasonably broad test guide might be 20 to 50 percent less liquid nitrogen is required per batch for a 10 to 15 percent shorter batch cycle.

An ideal liquid nitrogen control system should take into account the following considerations: The shortest possible cool-down time should be maintained when first commencing operation. The components of the system should be compactly arranged and sufficiently insulated to minimize, or efficiently utilize, the inherent boil-off of the liquid nitrogen. The arrangement of the components should be such that there is no entrapment of the liquid nitrogen between points where there is no pressure relief available. The distribution of the liquid nitrogen in the blast compartment should be uniform. The liquid nitrogen should be in the liquid state when it reaches the workpieces to effect the maximum cooling, and yet the spray device should be located in a position within the blast compartment so as not to obstruct the tumbling action of the work or the blast stream. The flow of the liquid nitrogen should be controllable by varying the flow rate and time cycle in proportion to the rate of B.t.u. dissipation required for a particular workpiece (to assure that the body of the work undergoes a minimum temperature drop and therefore does not become brittle; while at the same time, the flash undergoes a temperature drop adequate to embrittle it so that the impact of the abrasive will fracture the flash for rapid removal).

When considering the advantages and disadvantages of the liquid nitrogen system of the above ideal type as compared with carbon dioxide, the importance of uniform refrigerant distribution should be taken into account. It is more important in a liquid nitrogen system to have uniform distribution of the refrigerant in the blast compartment than for a carbon dioxide system. When liquid carbon dioxide (at 300 p.s.i.g. pressure and 0° F.) is forced from the nozzle of the header and enters the atmosphere, it converts to 54 percent cold gas (-109° F.) and 46 percent solid particles. These particles drop down in among the workpieces, and it is this physical contact that allows the greatest heat transfer. The tumbling action of the workpieces aids in the equal distribution of the solid carbon dioxide particles. Since the heat transfer coefficient between the work and solid carbon dioxide particles is lower than that of liquid nitrogen and the work, then the carbon dioxide system must tumble the parts longer to effect the same degree of cooling. This longer tumbling cycle allows more time for the carbon dioxide particles to distribute themselves. In the case of liquid nitrogen, however, there is a faster heat transfer from the work to the liquid nitrogen and therefore the work is cooled in a shorter period of time. Since there is a relatively less tendency for the liquid nitrogen to distribute among the work once it has contacted a workpiece and the time for distribution is shorter, the initial spray of liquid nitrogen in an ideal system must be evenly distributed from the header in the very beginning.

As can be appreciated, the lack of flow rate control in prior systems is a serious drawback. For example, lack of a precise flow rate control device in the system will make the accomplishment and repeatability of accurately controlled injections of liquid nitrogen into the blast compartment very difficult. Additionally, lack of such a device will make maximum economy impossible. Moreover, a system without a flow rate control is dependent on the pressure of the user's storage tank to determine the weight of liquid nitrogen that will flow through a piping arrangement of fixed cross-sectional area.

An object of this invention is to provide a liquid nitrogen deflashing apparatus which fulfills the above criteria of an ideal system.

A further object is to provide such an apparatus in which the rate of flow of the liquid nitrogen is accurately and conveniently controlled.

Novel features and advantages of the present invention will become apparent to one skilled in the art from a reading of the following description in conjunction with the accompanying drawings wherein similar reference characters refer to similar parts and in which:

FIGURE 1 is a section of one embodiment of this invention;

FIGURE 2 is a top view of a portion of the apparatus shown in FIG. 1;

FIGURE 3 is a section of the portion of the apparatus shown in FIG. 2; and

FIGURE 4 is an enlarged detail partially sectioned of a header used in the apparatus of FIGS. 1-3.

As shown in FIGURE 1, apparatus 10 is generally of the type described in Patent No. 3,110,983. Apparatus 10 includes a dehumidifying housing 12 and a tumbler 14 which supports and turns the workpieces. The freezing medium is applied to the workpieces through spray nozzle or header 16, while the embrittled excess material or flashing is removed by blast machines 18 which propel abrasive material against the cooled workpieces.

The liquid nitrogen system is best illustrated in FIGURES 2-3. As indicated therein, the liquid nitrogen is supplied through pipe 20, past relief valve 25 and into entrainment separator 22 which maintains as nearly as possible 100% liquid nitrogen to the header 16. From the entrainment separator 22 the liquid nitrogen flows through conduit 24 past flow control valve 26 and is eventually discharged from header 16 inside the housing 12 against the workpieces 28. Advantageously a shut-off control valve 30 is provided in line 24. The system also includes a vent line 32 which communicates between entrainment separator 22 and tumbler 14. A solenoid valve 34 is provided in this vent line 32. The various valves may be conveniently controlled through control panel 36 provided on the outside of housing 12.

An important feature of this invention is the provision of flow control valve 26. When designing for a certain cool-down rate it is best to design for an optimum time. It would be easy to design a system having no flow rate control and having all components of a thin walled construction. In such a system, all components would cool very quickly. However, a flow rate control is necessary if the system is to have broad range capabilities for a wide range of workpieces. Additionally, as later described, there are distinct advantages to having some of the components of a thick walled design. Flow rate valve 26 is so constructed that the liquid nitrogen system operates substantially independent of storage pressure. Of course, any sizable change in storage pressure will affect the flow. The important point being, however, that in the system of this invention the flow rate is not dependent on the storage pressure change for a change in flow rate. Advantageously the desired flow rate can be set by the operator through panel 36. Flow rate valve 26 operates by the pressure from carbon dioxide which flows through line 38 to chamber 40 to control the movement of valve element 42 disposed in liquid nitrogen line 24. The flow rate valve 26 may be for example, a parabolic needle type valve in which a pressure indicator is calibrated to establish a linear relationship between the pressure of the carbon dioxide and the extent of valve closing of valve element 42 in line 24. Valve element 42 may for example, be attached to a moveable diaphragm wherein the movement of the diaphragm 39 is determined by the amount of carbon dioxide and thus the pressure in the upper portion of chamber 40. The flow of carbon dioxide is controlled by manual control valve 41, adjacent pressure indicator 43 (FIG. 3).

As indicated above, control of flow rate of liquid nitrogen is maintained by the use of a diaphragm

operated flow control valve 26. The diaphragm, which controls the parabolic orifice in the flow control valve is activated by the use of dry carbon dioxide gas where orifice opening and/or flow rate are in direct proportion to the carbon dioxide pressure. The carbon dioxide pressure is controlled manually by the operator at control panel 36.

By the provision of flow rate control valve 26, the system of this invention is more economical than if the system were dependent on storage pressure to change the flow. For example if the system were dependent on storage pressure any time a different flow was required, the storage tank pressure would have to be changed. When an increase in pressure were required, the pressure gauge setting on the storage tank would have to be adjusted and the operator would have to wait for the pressure to build up. When a decrease in pressure were required, then the storage tank would have to be vented and nitrogen gas expelled. The waste that occurs during this adjustment varies with many factors; a few of which are the liquid level in the tank, the change in pressure desired, and the level of saturation of the nitrogen gas in the tank.

Another important feature of this invention is the provision of header 16. As best illustrated in FIGURE 4, line 24 terminates in T mounting 44. A nozzle 46 is for example threadably secured in each leg of mounting 44. The threaded engagement permits the nozzles to be rotated to change their orientation as required for different workpieces. As later described, nozzles 46 are thick walled having for example, a one inch outside diameter and a $2\frac{1}{4}$ inch inner diameter. Thus, the spray aperture 48 are for example, approximately $1\frac{1}{32}$ inch long. Additionally, the diameter of each spray aperture 48 decreases from T mounting 44 toward the outer end of each nozzle 46. The distance between each aperture 48 may be for example, two inches.

The above described header 16 is specifically designed to provide even distribution of liquid nitrogen. Normally liquids undergo a pressure drop as they move from the center T of the header toward the extreme ends. Liquid nitrogen, however, actually increases its pressure by its expansion from a liquid to a gas. The size and arrangement of apertures 48 are designed to compensate for this characteristic and thus assure an even flow from the header along its entire length.

Not only is the design of the header so very important for the reason described above, but its ability to maintain the greatest percentage of nitrogen in the liquid form right down to the time when it contacts the work, is another key function of header 16. In this sense, the thick walled construction of nozzles 46 is not in accordance with the generally accepted practice of manufacturing the header of a thin walled tube. This departure to thick walled tubing, however, has two great advantages. First, the spray apertures 48 provide an orifice effect that propels the liquid nitrogen greater distances more effectively with less vaporization than a hole in a thin walled header. Secondly, the thick walls tend to lessen the heat transfer from the atmosphere to the liquid nitrogen within the header. Combined, these two features permit the nitrogen to be delivered in a liquid state to the work.

With header 16 it is possible for example, to provide a system which requires 9 pounds of liquid nitrogen and only about 20 minutes to cool down to an operating temperature of -320° F. Thus, the deflashing can take place with greater efficiency than in prior apparatus.

The effectiveness of the header 16 would be lessened if 100 percent liquid flow were not provided to the header. As described hereinafter, entrainment separator 22 maintains a liquid level at all times and therefore there is 100 percent liquid flow through the flow rate valve 26 to the header 16 every time shut-off valve 30 is opened.

An important advantage of this invention is the utilization of any boil-off to act as supplementary coolant. Since liquid nitrogen will boil-off despite any reasonably eco-

nomic preventive methods, this system not only minimizes the boil-off but actually uses the nitrogen gas to aid in the cooling action. In this respect, the system is physically compact and well-insulated. For example, as shown in FIG. 2 entrainment separator 22 has foamed-in-place polyurethane foam 50 between the inner and outer stainless steel walls 52, and the entrainment separator 22 is designed for minimum external surface for minimizing heat transfer from the atmosphere to the liquid nitrogen therein. The boil-off gas in entrainment separator 22 is advantageously conveyed through line 32 to the tumbler 14 (FIG. 3). This helps maintain a lower temperature within the blast compartment and also limits the vaporization of the liquid nitrogen as it exits from header 16. The gas flow due to boil-off (-320° F.) is controlled through shut-off solenoid valve 34 to avoid over-cooling certain workpieces.

The components of the system are located for maximum safety and avoid the danger of entrapping liquid nitrogen in an area where the expanding gases could cause an explosive condition. The arrangement is also compatible with the user's main storage tank and the associated pressure and shut-off controls. Moreover, strategically placed pressure relief valves give positive protection.

Obviously, many modifications and variations of the present invention are possible in the light of the above teachings. It is, therefore, to be understood that within the scope of the appended claims the invention may be practiced otherwise than as specifically described.

What is claimed is:

1. In an apparatus for deflashing excess material from workpieces including a dehumidifying housing, means for supporting the workpieces within the housing for simultaneously supporting and turning the workpieces, freezing medium applying means for applying freezing medium to the workpieces to lower their temperature thereof, and abrasive blasting means supported within the housing adjacent the supporting and turning means for propelling abrasive particles against the cooled workpieces to remove excess material therefrom, characterized in that said freezing medium applying means includes means for connection to a source of supply of liquid nitrogen, an applicator head adjacent the supporting and turning means, conveying means for conveying liquid nitrogen from the source of supply to the applicator head, means for varying the rate of flow of the liquid nitrogen in said conveying means substantially independently of the storage pressure of liquid nitrogen in the source of supply, and means for conveying boiled-off nitrogen gas to the supporting and turning means.

2. In an apparatus for deflashing excess material from workpieces including a dehumidifying housing for simultaneously supporting and turning the workpieces, freezing medium applying means for applying freezing medium to the workpieces to lower their temperature thereof, and abrasive blasting means supported within the housing adjacent the supporting and turning means for propelling abrasive particles against the cooled workpieces to remove excess material therefrom, characterized in that said freezing medium applying means includes means for connection to a source of supply of liquid nitrogen, an applicator head adjacent the supporting and turning means, conveying means for conveying liquid nitrogen from the source of supply to the applicator head, means for varying the rate of flow of the liquid nitrogen in said conveying means substantially independently of the storage pressure of liquid nitrogen in the source of supply, and said means for varying the rate of flow includes a

flow rate valve operable by a control gas other than nitrogen.

3. In an apparatus as set forth in claim 2 wherein said means for varying the rate of flow of liquid nitrogen includes a manual shut-off valve for the control gas.

5 4. In an apparatus as set forth in claim 3 wherein said manual shut-off valve is disposed upon a control panel mounted externally of the housing.

10 5. In an apparatus as set forth in claim 1 wherein said applicator head includes a dual header comprising a T mounting, a pair of nozzles secured in said T mounting, a plurality of spray holes in each of said nozzles, and the diameter of each spray hole decreasing from said T mounting to the tip of each nozzle.

15 6. In an apparatus as set forth in claim 5 wherein adjustable mounting means secure said nozzles to said mounting for varying the orientation of said spray holes.

7. In an apparatus as set forth in claim 1 wherein said 20 conveying means includes an entrainment separator between the source of supply and the supporting and turning means, and said means for conveying boiled-off nitrogen gas including a conduit between said entrainment separator and the supporting and turning means.

8. In an apparatus as set forth in claim 1 wherein said 25 conveying means includes a shut-off valve for controlling the on and off flow of the liquid nitrogen.

9. In an apparatus as set forth in claim 1 wherein said 30 conveying means includes an entrainment separator between the source of supply and the supporting and turning means, the walls of said entrainment separator being made of foam material disposed between layers of stainless steel, said means for conveying boiled-off nitrogen including a vent line leading from said entrainment separator to said supporting and turning means, means for 35 varying the rate of flow of liquid nitrogen including a parabolic needle valve, a moving member connected to one end of said needle valve, the other end of said needle valve being disposed for seating in said conveying means, means for conveying carbon dioxide control gas on the 40 side of said moving member remote from said conveying means to move said needle valve in accordance with the pressure of the control gas, a manually operable carbon dioxide pressure regulator connected in said means for conveying the control gas, said conveying means including a safety valve between said entrainment separator and said header, a shut-off control valve in said conveying means, said shut-off control valve being disposed on a control panel mounted externally of the housing, said header including a T mounting, a pair of outwardly extending nozzles threadably secured to said T mounting, a

45 plurality of spray apertures in each of said nozzles, each of said apertures being approximately $1\frac{1}{32}$ inch long, and said apertures being equally spaced from each other and decreasing in diameter away from said T mounting.
